Isaac Rulofson

UNITED STATES PATENT OFFICE.

ISAAC RULOFSON, OF PENN YAN, NEW YORK.

IMPROVEMENT IN PLOWS.

Specification forming part of Letters Patent No. **23,116**, dated March 1, 1859.

To all whom it may concern:

Be it known that I, ISAAC RULOFSON, of Penn Yan, in the county of Yates and State of New York, have invented new and useful Improvements in Plows; and I do hereby declare that the following is a full, clear, and exact description of the construction and operation of the same, reference being had to the accompanying drawings, making a part of this specification, in which—

Figure 1 is a perspective view of the whole plow. Fig. 2 is an inside view of the landside part or standard of the plow. Fig. 3 is a view of the inside of the mold-board separate.

The letters of reference refer to the same parts in each figure.

A, Fig. 1, is the beam. The forward end may be made as represented, or in any other manner. The rear end is made with a doved-tailed wedge-shaped piece on each side of the beam. These pieces are made to fit into either side of the standard, as represented by the drawings.

B is a standard. The lower part constitutes the landside portion of the end support for the left handle. The upper part is made to receive the wedge-shaped pieces of the beam in either side. These joints may be made to receive thin wedges to give direction to the beam when required. A bolt may be put through the center to give more firmness to the joint. On the inside of this portion are mitered cleats F F, that receive and hold the part G of the mold-board.

C is the mold-board, with nothing peculiar on the furrow side; but on the land side is the part G, which is narrower at the rear end than it is at its union with the mold-board. It is

mitered and made to fill the space between the cleats F F, so that when these parts are drawn together they form a firm and unalterable joint and keep the plow in proper shape.

D is a landside-strip, which is of the ordinary construction.

E is the share, with nothing peculiar in its construction, except that it is fitted to the mold-board only.

F and F are mitered cleats, and made on and with the part B. They hold the parts B and C firmly together.

G is a wedge-shaped piece, mitered so as to fill up the space between the cleats F and F. This with the cleats forms the connection of the mold-board and standard.

H is a piece fitted to the upper edge of the mold-board. It is held in place by means of mitered projections at its lower edge that pass down between the cleats I. It is made to be taken off or put on at pleasure when needed. Its use is to enlarge the mold-board when plowing deep, or when the soil will fall over the mold-board without it.

I represents the cleats, that are on the inside and upper part of the mold-board. They are mitered to hold between them the projections of the part H.

What I claim, and desire to secure by Letters Patent, is—

The arrangement of beam A, standard B, landside-strip D, share E, mold-board C, and piece H, the whole being constructed and united as and for the purpose herein set forth.

ISAAC RULOFSON.
